UNITED STATES PATENT OFFICE.

CHRISTIAN HENRICHSEN, OF PITTSFIELD, MASSACHUSETTS, ASSIGNOR TO GENERAL ELECTRIC COMPANY, A CORPORATION OF NEW YORK.

ARC-LAMP.

1,159,765.

Specification of Letters Patent.

Patented Nov. 9, 1915.

Application filed July 11, 1913. Serial No. 778,509.

To all whom it may concern:

Be it known that I, CHRISTIAN HENRICHSEN, a subject of the King of Denmark, residing at Pittsfield, county of Berkshire, State of Massachusetts, have invented certain new and useful Improvements in Arc-Lamps, of which the following is a specification.

My invention has reference to an inclosed flame arc lamp. In lamps of this character, electrodes are used which contain mineral salts or compounds, and an arc supported by such electrodes evolves solidifiable products of combustion, which readily deposit on any surface with which they come in contact, and when they deposit upon the inclosing globe, they obstruct the light and reduce the efficiency of the lamp.

One object of my invention is the provision of a novel form of arc inclosure comprising a condensing chamber located above and remote from the globe, the whole being so constructed as to produce a vigorous circulation of the gases evolved from the arc above the globe where most of the condensable fumes are deposited. The fumes are thus largely relieved of their condensable products of combustion, and when the purified gases return to the globe, little if any deposit takes place on that part of the globe through which the light passes.

Another object of my invention is the provision of a structure which produces a circulation of the character above indicated and to which access is readily had for the purpose of cleaning the same.

Other novel features of my invention will appear in the specification and will be pointed out in the claims.

For a fuller understanding of my invention, reference may be had to the accompanying drawing, which represents a vertical sectional view of a lamp showing the preferred form of my invention.

The lamp is supported from a top plate 1 by a bail or strap 2, which is suspended by the usual pulley 3 of insulating material. A central draft tube 4 is externally threaded at its upper end and is received within an internally screw-threaded flange 5 on the top plate 1. The upper end of the draft tube is provided with openings 6 for a purpose hereinafter more fully set forth. The upper end of a hood 7 for the collection of the fumes evolved from the arc is received

around the lower end of the draft tube 4 and suitably secured thereto. An annular bottom plate 8 is secured to the lower edge of the hood 7.

An economizer 9 of copper or other suitable material is supported by means of a bolt 10 from a frame 11 comprising a number of substantially vertical or slightly inclined ribs 11^a and a cylindrical ring 12 at the upper end, which ring is received within the draft tube 4. The lower ends of the ribs are provided with horizontal extensions 11^b which are suitably secured to the hood 7. A bushing 13 of lava or other refractory material is received within a central opening 70 in the economizer 9 and closely surrounds the upper electrode 14.

A condensing chamber 15, which is of large superficial area and exposed to the atmosphere, is located above and remote 75 from the arc-inclosing globe; it is made of two shells 16, 17, which join in a horizontal plane. The upper and lower shells are secured together by clamps 18 pivoted at 19 on lugs secured to the upper shell and engaging lugs 20 on the lower shell.

An annular plate 21 having downwardly extending flanges at its inner and outer edges is secured to the draft tube 4 immediately below the openings 6. A cylindrical 85 inner casing 22 is received at its upper end over the annular plate 21 and at its lower end over the bottom plate 8 and forms a substantially air-tight joint with both of these plates.

An outer shell 23, which constitutes an ornamental casing for the lamp is spaced from the inner casing 22 and secured thereto by studs 24 and is secured to and supported from the lower shell 17 of the condensing 95 chamber and forms, with the inner casing, an annular space 25 which communicates above with the condensing chamber and below with the inclosing globe.

A reflector 26 of any suitable form is secured to the lower part of the outer casing 23 and supports and forms a substantially air-tight fit with an annular plate 27 against which the globe 28 is seated.

The upper end of the upper electrode 14 105 is received within a weighted electrode-holder 29 which is preferably made triangular in form so as to permit the fumes evolved from the arc to pass the electrode-holder within the draft tube. The electrode- 110

holder is suspended by a flexible connection 30 passing over a sheave 31 of a pulley 32 which is mounted in brackets 33 upstanding from the top plate 1 of the lamp. A lower electrode 34 is received within an electrode-holder 35 carried by an electrode supporting rod 36 which passes through a sleeve 37 in the bottom plate 8. The upper end of the rod 36 is provided with a guide block 38 having a roller 39 which engages a guide rod 40 extending between the top and bottom plates of the lamp. The block 38 is suspended by a flexible connection 41 from a second sheave 42 of the pulley 32, the connection 41 passing through a sleeve 45 secured in the top plate 1 and annular plate 21. The clutch pulley 32 is provided with an arm 43 to which is pivoted a link 44 extending to the operating mechanism of the lamp which is located between the draft tube and the inner casing 22.

I have not here shown the operating mechanism of the lamp nor the details of the clutch mechanism, since these form no part 25 of my invention and since any well known clutch pulley and operating mechanism may be used, as is well understood by those skilled in the art.

The lower shell of the condensing chambers is preferably provided with an annular rim 46 which holds in position pieces 47 of any suitable material, such as lime, which are preferably used for absorbing noxious gases and moisture and thereby preventing 35 or tending to prevent the fumes from etching the globe.

In operation the fumes evolved from the 40 arc ascend around the economizer 9 and are collected in the hood 7 and then pass upwardly through the draft tube 4 and through the openings 6 in the top thereof to the condensing chambers 15. The gases are cooled in this chamber and are relieved of much of their solidifiable products of combustion 45 and the gases thus cooled and purified pass downwardly through the passage 25 formed between the two casings 22 and 23 to the top of the inclosing globe.

I have found in practice that the structure embodied in my invention and comprising a condensing chamber located above and remote from the arc inclosing globe induces a vigorous circulation of the gases evolved from the arc which is beneficial in preventing 50 deposits on the inclosing globe; the large radiating surface of the outer casing contributes to this result. In any case, I find in actual practice that the globe in a lamp embodying my invention remains remarkably 55 clean.

In accordance with the provisions of the 60 patent statutes, I have described the principle of operation of my invention, together with the apparatus which I now consider to 65 represent the best embodiment thereof; but

I desire to have it understood that the apparatus shown is only illustrative, and that the invention can be carried out by other means.

What I claim as new and desire to secure 70 by Letters Patent of the United States, is,—

1. In an arc lamp, a top plate, a substantially air-tight arc inclosure comprising a globe surrounding the arc and a condensing chamber located above and remote from the 75 globe, the upper wall of the chamber being seated against and secured to the top plate, a central draft tube secured to the top plate, and communicating at its lower end with the globe and having lateral openings at its 80 top communicating with said condensing chamber, and two shells concentric with said draft tube and forming an annular passage communicating with the globe and with said condensing chamber.

2. In an arc lamp, top and bottom plates for the lamp, a circulatory system for the gases evolved from the arc comprising a horizontally divided condensing chamber, the upper part of which is seated against 90 and supported from the top plate, an annular plate supported from the top plate, two shells secured together and supported from the lower part of the condensing chamber, the inner shell being received over the 95 bottom plate and said annular plate, and a globe supported by the outer shell, the shells being suitably spaced apart to form an annular passage between the condensing chamber and said globe, and means for securing 100 the lower part of the condensing chamber against the upper.

3. In an arc lamp, top and bottom plates for the lamp, a horizontally divided condensing chamber, the upper part of which is seated against and supported from the top plate, a central draft tube secured to the top plate, an annular plate secured about said draft tube and forming a part of the condensing chamber, two spaced circular shells secured 105 together, the inner of which is received over the bottom plate and said circular plate, and the outer of which is supported from the lower part of the condensing chamber, and a globe supported from the outer shell, the 110 two shells forming an annular passage communicating with the globe and the condensing chamber and forming, with the globe, draft tube and condensing chamber, a substantially air-tight arc inclosure.

4. In an arc lamp, top and bottom plates, a condensing chamber seated against and supported by the top plate, a central draft tube secured to the top plate and forming the back bone of the lamp and communicating with the condensing chamber, and two spaced shells secured together and supported from the condensing chamber and forming a passage which communicates with the condensing chamber, a globe surrounding 115

the arc communicating with said draft tube and with said passage, and a clutch pulley mounted upon the top plate from which one of the electrodes is suspended within said draft tube, and a sleeve passing through the condensing chamber through which the other electrode is suspended.

In witness whereof, I have hereunto set my hand this 7th day of July, 1913.

CHRISTIAN HENRICHSEN.
